Patent expires February 28, 1966

9 Claims. (Cl. 81—17)

1

The present invention relates to a machine-tool vise of the type having a movable jaw and a shoe, both adapted to slide on a guiding member secured to a stationary jaw, in a direction at right angles to clamping faces of the jaws, locking means being adapted to lock the shoe on the stationary guiding member, and clamping means being adapted to move the movable jaw and the shoe relatively to each other.

One object of the present invention is to provide means for automatically locking the shoe on the stationary guiding member at any position on said guiding member when clamping the movable jaw against a workpiece.

Another object of the invention is to provide connecting means between the movable jaw and the shoe adapted to exert a downward force on the movable jaw and to tend to lower said movable jaw positively with relation to the shoe, when the clamping means tend to move the movable jaw towards the stationary jaw and to move the shoe away from said stationary jaw.

In the accompanying drawings, which are given only by way of example:

Fig. 1 is a vertical composite section of a first embodiment of a vise along the lines 1—1 and 1'—1' of Figure 3 passing respectively through the axis of symmetry of the locking blades for the shoe and through the axis of the tightening screw.

Fig. 2 is a partial transverse vertical section along the line 2—2 of Fig. 3.

Fig. 3 is a horizontal section of said vise.

Fig. 4 is an explanatory diagram of the locking device for the shoe.

Fig. 5 is a longitudinal vertical composite section of a second embodiment taken along the lines 5—5 and 5'—5' of Figure 8 passing respectively through the axis of symmetry of the locking blades for the shoe and through the axis of the tightening screw.

Fig. 6 is a partial vertical section along the line 6—6 of Fig. 8.

Fig. 7 is another partial vertical section along the line 7—7 of Fig. 8 showing the shape of a flexible blade of the locking means for the shoe, and the cross-section of the members connecting the front part to the rear part of the movable jaw.

Fig. 8 is a plan view, partly in section, of the vise shown in Figs. 5 to 7.

Fig. 9 is a section along the line 9—9 of Fig. 5.

Fig. 10 is a vertical section of a modification of the movable jaw comprising a separately fitted cheek.

2

Like numerals designate like parts in all the figures.

According to the embodiment of Figures 1 and 2, the vise comprises a stationary jaw 1, secured to a base 2 in which are provided inverted T-shaped longitudinal grooves 3, and a movable jaw 4 secured to an inverted U-shaped frame 5 and a rear cross-member 11. Said frame (5—11) is connected by means of two vertical flexible metal blades 6 and 7 to a shoe 8 adapted to slide on the base 2.

The blades 6 and 7 are fixed by any suitable means, for example by means of rivets or screws 40, 41, to the cross-members 4 and 11 and the shoe 8.

At the rear in the cross-member 11 of the frame is provided a bore 12 for passing a horizontal screw 13 which is arranged in the axis of the movable assembly and passes loosely through the blade 7 which is provided for this purpose with a hole of sufficient size and screws into a tapped hole 42 of the shoe 8. Said screw 13, which is provided with a head 15 with several sides for controlling it from outside, is held in the longitudinal position by its collar 16 and by a plate 17 which is fixed to the cross-member 11.

According to the invention, the shoe 8 is provided, on its lower face, opposite each groove 3 of the base 2, with a cavity 44 of rectangular cross-section and, on its upper face, with a cut out portion 45 having a shape abcdef of greater width than that of the cavity 44, it being possible for said cut out portion to extend in a direction at right angles to that of Fig. 1, over the entire width of the shoe. Said cut out portion intersects the or each cavity 44 in such a manner as to form on the edges of said cavity two bearing surfaces 46. On the two bearing surfaces thus formed bear downwardly, by the lower edges of two lateral wings 47 and 48 (Fig. 2), steel blades 49 which are pressed against one another. Said blades 49 are T-shaped in front elevation (see Fig. 2). They are provided in their bases with a T-shaped or like recess 50, by means of which each of them is passed over the head 51 of a slider 52 of double T-shape, housed with a widthwise clearance in the groove 3 of the base 2, whereby the movable jaw, together with the shoe 8 may assume a sloping position in the traverse direction so as to enable the jaw to adapt itself to the possible non-parallelism of the opposite clamped faces of the workpiece.

The bundle of blades 49 is held on the slider 52 against two lateral abutments 54 by means of a plate 55 fixed by means of screws 56 or other-

wise to the slider. Preferably, the opposite faces of the plate 55 and of the abutments 54 of the slider have a slight outward taper towards the top in order to allow the bundle of blades to rock slightly. Furthermore, a bearing member 51, engaged in the opening 45 of the shoe 8, to which it is fixed by means of screws 58 or otherwise, bears downwardly against the top of the bundle of blades and prevents it from moving upwards when unclamping.

To the slider 52 is fixed, towards the rear, by screwing or otherwise, a rod 59. Said rod passes loosely through the shoe 8, the blade 7, the cross-member 11 and is provided, outside said cross-member, with a stop nut 60 and a lock-nut 61.

Finally, a coil spring 62 is arranged on the rod 59 between the slider 52 and the wall of the cavity 44 of the shoe 8.

The operation is as follows:

For clamping a part 18 between the jaws 1 and 4, the movable jaw assembly, i. e. the shoe 8 with its slider 52, the frame (5, 11) and the jaw 4, is moved towards the left as a whole, on the base 2. At this instant the spring 62 holds the nut 60 against the cross-member 11. As soon as the jaw is in contact with the part 18, clamping is effected by rotating the screw 13 in the direction which screws it into the part 8. This produces a relative movement of the frame (5, 11) and the shoe 8. The frame (5, 11) clamps the part 18 whereas the shoe 8 tends to move towards the right. It carries with it the upper ends of the blades 49 which may be assimilated (Fig. 4) to a link 49a which is pivotally connected, on the one hand to the shoe 8 at O¹, and on the other hand to the slider 52 at O². The assembly comprising the slider 52, the blades 49 and the shoe 8 is nothing more than the well-known clamping device comprising blocks 8a and 52a connected to one another by a link 49a (Fig. 4). With such a device, as can be seen, as soon as tightening is started, since the slider or block 52a cannot slide owing to its friction against the guideway 3, the force F² exerted on the block 52a in the direction O¹O² owing to the tightening force F¹ forms with the perpendicular to the bearing surface 3 an angle α which is smaller by construction than the angle of friction φ . Under these conditions, the more the force F¹ acts, the more 52a is jammed.

In an identical manner, the greater is the tightening force of the vise, and provided that the slider 52 already has a tendency to adhere in the groove 3, the greater will be the adhesion of the slider to the base 2, since in this construction, as in the theoretical construction, the dimensions and shapes are such that the angle α of the force F² is smaller than the angle φ of friction of the blades against their two bearing surfaces and of the slider 52 against the upper faces of the groove 3.

When at the beginning of the operation, the assembly formed by the movable jaw, the shoe and the slider has been pushed towards the stationary jaw, it was possible to push the movable jaw forwards, towards the left (Fig. 1) since in this direction there is no clamping. On the other hand, as soon as tightening by means of the screw 13 begins, the slider 52 and the shoe 8 are locked. The initial adhesion required for the locking is produced by the spring 62 which, even before the tightening, tends to move the slider 52 relatively to the shoe 8 towards the left (Fig. 1), thereby increasing the slope of the blades 49 and, consequently, produces the initial adhe-

sion required for locking the slider and the shoe to the guideway 2.

The assembly 4, 5, 11 rests on the base 2 when the blades 6 and 7 are vertical. But when said assembly 4, 5, 11 tends to move towards the stationary jaw 1 by the action of the tightening screw 13 entering into the shoe, the blades 6 and 7 which are retained at their lower part by the locked shoe 8 follow at their upper part the movement of the assembly 4, 5, 11, thus causing a resilient elongation of the blades 6 and 7 corresponding to a tensile stress between the shoe and the assembly 4, 5, 11. Since the shoe is pressed upon the base by the blades 49, the movable jaw 4 is pulled downwards and cannot be lifted away from its base 2.

It should be observed that the backward movement of the movable jaw at the end of the operation would be impossible without an auxiliary device which pulls the slider 52 towards the right relatively to the shoe 8 and thereby eliminates the locking adhesion. This is the purpose of the rod 59. In fact, when unclamping, i. e. when, by means of the screw 13, the frame (5, 11) is moved towards the right relatively to the shoe 8, the cross-member 11, after effecting a travel e' , encounters the stop nut 60 supported by the rod 59. Said rod is moved towards the right, pulls the slider 52 and, as the shoe 8 is still locked, the blades 49 tend to become vertical (see Fig. 4 in which the point O' would move towards the right) thereby automatically unclamping the parts 8 and 52. The movable jaw assembly can then be moved towards the right.

As can be seen, by means of the device described, clamping and unclamping are absolutely automatic.

According to the embodiment of Figs. 5 to 9, the vise comprises a stationary jaw 70 secured to a base 71 in which are provided longitudinal grooves 72 of inverted T-shape and a movable jaw 73 rigidly assembled by means of screws or otherwise to the frame 74 which is of the shape of an inverted box from which the front side is missing and is replaced by the jaw 73. The movable jaw 73 is connected by means of a vertical flexible blade 75 to a shoe 76 sliding on the base 71. The blade 75 is fixed by any suitable means for example by means of rivets 77, to the movable jaw 73 and to the shoe 76.

In the rear cross-member 78 of the movable frame 74 is provided a bore 79 for passing a horizontal screw 80 which is arranged in the axis of the movable system and screws into a tapped hole 81 of the shoe 76. Said screw 80, which has a head 82 with several sides for enabling it to be controlled from outside, is held in the longitudinal position by its collar 83 and by a plate 84 which is fixed to the rear of the movable frame.

The shoe 76 is provided, opposite each groove 72 of the table 71, with a cavity 85 of rectangular cross-section and on its upper face with a cut-out portion 86 of the shape abcde which may extend over the entire width of the shoe so as to form on the edges of each cavity 85 two surfaces 87 against which bear downwardly, by the lower edges of two wings 88 and 89 (Fig. 6), steel blades 90 which are pressed against one another. Said blades are of I-shape in front elevation and are provided with two lower wings 91 which are adapted to bear against bars 92 of a slider 93 lodged in the groove 72 of the base 71.

The bundle of blades 90 is held on the bars 92, 75 at the rear by the slider 93 and at the front by

a cross-member 94 connecting the two bars 92 by means of tapered pins 95 or otherwise, the slider 93 and the cross-member 94 being of such a shape as to allow of a slight tilting of the blades 90. Two springs 96 and 97 which are fixed by means of screws or otherwise underneath the shoe, opposite the sliders, facilitate the separation of the bars 92 from the overlying bearing surfaces of groove 72 when unclamping. Into the slider 93 is screwed at the rear thereof a screw 98 which passes through the rear wall 78 of the movable frame 74 and the head of which is adapted to bear against the outside of said wall. Finally, a coil spring 99 is arranged on the screw 98 between the slider 93 and the rear wall 78 of the movable frame.

The frame 74 can slide on two cylindrical guides or studs 100 which are secured to the shoe 76 and engage in corresponding bores of the rear wall 78 of the frame 74. Said studs 100 act as guides for the frame 74 at the rear and ensure the correct movement of said frame.

A compression bar 103 adapted to slide loosely in a groove 104 of the shoe 76 braces the movable jaw 73 and the rear wall 78 of the frames 74 and is held in position by two small positioning pins 105 located at each end and penetrating slightly into the jaw 73 and the wall 78.

The movable jaw 73 rests against the base 71 of the stationary jaw only by means of a narrow bearing surface 106 in such a manner that the bent portion 107 is not supported at the rear and can bend when a downward vertical force is exerted on the jaw 73 owing to the increasing slope of the flexible blade 75 during the tightening.

The separately fitted cheek 108 of the stationary jaw 70 has an inclined face 109 which bears directly with its lower part 110 on a cooperating face of the stationary jaw 70 and with its upper part 111 on a bundle of blades 112 at right angles to their faces, said blades bearing against the stationary jaw 70 and the separately fitted cheek 108. Said blades 112, which perform the function of rollers eliminating the sliding friction, are held in a suitable position on one side by a plate 113 of rectangular cross-section which is fixed to the separately fitted cheek 108 and on the other by a thin corrugated spring 114 (Fig. 9) bearing against a shoulder 115 of the jaw 108. Two screws 116, screwed in a tapping of the cheek 108, are locked by lock-screws 117, the adjustment being effected in such a manner that a perfect contact is obtained between the cheek 108 and the stationary jaw 70 without appreciable pressure. Said screws pass loosely through the stationary jaw so that they are free transversely between their head and the cheek 108 which rests against the end 118 of an overhanging flexible tongue 119 integral with the stationary jaw 70.

The operation is as follows:

The screws 98 are adjusted in such a manner that when the movable jaw is at the end of its rearward travel, the bars 92, urged by the springs 96 and 97, move slightly away from their bearing surface in the grooves 72 of the base 71 of the stationary jaw 70 so as to permit the movable jaw system to slide readily on the base 71 of the stationary jaw 70.

The part to be clamped 122 being placed on wedges 120 and 121, the movable jaw is moved forwards by hand against the part so that this latter is firmly in contact both with the movable jaw and with the stationary jaw.

The side play in the grooves 72 enables the movable jaw to be orientated slightly in order to obtain this contact in a suitable manner if the two faces to be clamped are not absolutely parallel.

Next, the tightening screw 80 is actuated and causes the shoe 76 to move backwards, since the movable jaw 73 cannot move further forwards.

The bars 92 remain stationary in the longitudinal direction, because they are connected to the frame 74 by the action of the heads of the screws 98 and of the springs 99.

As the shoe 76 moves backwards, it produces on the one hand an inclination of the flexible blade 75 which first tends to cause the shoe 76 to move upwards, the movable jaw 73 resting with its part 106 against the base 71, and on the other hand an increase in the slope of the blades 90 which tends to lift the bars 92 and bring them into contact with their bearing surface in the grooves 72.

From this instant, there is adhesion of the bars 92 in the groove 72 and as the force which presses them against their bearing surface is directed along the axis of the blades, forming with the perpendicular to said surface a smaller angle than the angle of friction, they can no longer slide in the grooves 72.

As the tightening movement continues, the shoe 76 moves more and more backwards, and the blades 90 have to become elongated, which subjects them to an increasing tensile stress which presses the shoe 76 more and more firmly against the base 71 of the stationary jaw. At the same time, the blade 75, as it becomes more and more inclined, tends to press the movable jaw 73 more and more firmly against the base 71, thereby causing the bent portion 107 of the jaw 73 to bend and finally producing a downward movement of the movable jaw 73 and consequently the compression of the clamped part 122 against the wedge 120 which supports it on the movable jaw side.

It will be observed that, upon clamping the work piece between the jaws, a spring 99 enables the slider to remain stationary during a slight movement of the movable jaw towards the work piece, the latter being caused by an elastic deformation of that area of said movable jaw 73 in contact with said piece 122.

On the other hand, the tightening force, owing to the inclination of the bearing face of the separately fitted cheek 108 against the stationary jaw 70, has a vertical component which presses said cheek 108 against its lower rest formed by the flexible tongue 119, which bends and enables the cheek 108 to move sufficiently downwards to compensate the lifting of the part from the wedge 121 which occurs with a stationary jaw which is not provided with this device. The screws 116 only offer a negligible resistance to the very slight movement of the separately fitted cheek 108, since they are loosely mounted in stationary jaw 70 and can bend and rock slightly.

If α is the angle which the oblique bearing face of the separately fitted cheek forms with the vertical, φ the angle of sliding friction on the lower part 110 of said face, and if the friction on the rest 111 is considered to be practically nil because of the blades 112 acting as rollers, if F_1 is the part of the tightening force F supported by the rest 110, and F_2 that of the rest 111, then:

and the vertical component of the force F on the separately fitted cheek 108 is:

$$F_1 \tan(\alpha - \varphi) + F_2 \tan \alpha$$

If $F_1=F$, $F_2=0$, case in which the part is clamped right opposite the rest 110, the component is:

$$F \tan(\alpha - \varphi)$$

If $F_2=F$, $F_1=0$, case in which the part is clamped at the top right opposite the rest 111, the component is:

$$F \tan \alpha$$

It is obvious that the force acting to lower the separately fitted cheek 108 will be greater for a given tightening force F as the part is clamped higher.

Now the lifting of the part 122 with an ordinary stationary jaw would be more pronounced as the part is clamped higher.

It is therefore possible to compensate in practice this lift by a corresponding lowering of the separately fitted cheek 108, so that the part no longer lifts off its wedge 121 but is slightly pressed against said wedge.

The movable jaw may be provided with a separately fitted cheek arranged exactly in the same manner as in the stationary jaw 10. Fig. 10 shows the movable jaw 73' provided with the separately fitted cheek 108' having an inclined face 109' which bears with its lower part directly on a cooperating face of the jaw 73' and with its upper part 111' on a bundle of blades 112' under the action of a spring 114'. Screws 116' provide for a perfect contact between the cheek 108' and the jaw 73'. The cheek 108' rests on the end 118' of an overhanging tongue 119' integral with the movable jaw. Said separately fitted cheek 108' has the same function as the cheek 108 in the stationary jaw 10 and replaces the bent portion 107 of Fig. 5.

The advantage of the foregoing devices for compensating the lifting of the part, both on the stationary jaw side and on the movable jaw side, over some devices having wedge-shaped jaws which can slide and which are held in the high position by very flexible springs, is that, contrary to what occurs with the latter, the use of wedges under the part is not necessary for stabilising the height of the part to be clamped during the tightening action.

The invention is obviously not limited to the embodiments illustrated and described which have only been given by way of examples and modifications may be made therein without exceeding the scope of the invention.

What I claim is:

1. A machine-tool vise comprising in combination a stationary jaw provided with a substantially vertical clamping face and with a substantially horizontal fixed guiding member directed at right angles to said clamping face and provided with at least one substantially horizontal inverted T-shaped groove extending at right angles to the clamping face of said stationary jaw, a movable jaw provided with a clamping face substantially parallel to the clamping face of the stationary jaw and slidable on said guiding member toward and away from the clamping face of said stationary jaw, a shoe slidable on said guiding member, a slider slidable in said groove of said guiding member, a bundle of juxtaposed locking blades bearing downwards on an upper part of said shoe and upwards on a lower face of said slider, said

locking blades being tilted at such an angle that said movable jaw, said shoe and said slider can move as a unit toward and away from said stationary jaw, and tightening means engaging said movable jaw and said shoe to move the movable jaw and the shoe relatively to each other for increasing the angle of tilt of the locking blades and for locking the shoe and slider on said guiding member, and to further move the movable jaw and the shoe relatively to each other so as to force the movable jaw toward the stationary jaw after locking of the shoe and slider on the guiding member, the tightening effort increasing with the inclination of the locking blades, and the adherence of the shoe on the fixed guiding member resulting from the elastic lengthening of said blades.

2. A machine tool vise according to claim 1, further comprising a rod operatively connected with said slider, and stop means carried on said rod to cooperate with said movable jaw when said tightening means are operated for shifting said movable jaw away from the stationary jaw so as to move said slider away from said stationary jaw, thereby reducing the angle of tilt of said blades and unlocking said shoe.

3. A machine tool vise according to claim 1, further comprising a spring interposed between the slider and the movable jaw to enable the slider to remain stationary and the movable jaw to move slightly towards the piece to be worked, when that area of the movable jaw in contact with a workable piece is elastically deformed during tightening of the vice.

4. A machine tool vice according to claim 1, further comprising a rod operatively connected with said slider, stop means adjustably carried on said rod to cooperate with said movable jaw, and a spring interposed between said slider and said movable jaw, whereby relative longitudinal positions of the movable jaw, the shoe, and the slider, when the slider begins to adhere in its groove, may be determined, so as to provide clearance for the unitary sliding movement of the movable jaw, the shoe, and the slider.

5. A machine tool vice according to claim 1, in which a widthwise clearance is provided between the slider and its guiding groove, whereby the movable jaw assumes an angular position with relation to the stationary jaw, when opposite faces of the piece being clamped are not absolutely parallel.

6. A machine-tool vise according to claim 1 further comprising at least one flexible blade connecting a forward and lower part of the shoe to a forward and upper part of the movable jaw, said flexible blade being continuously positioned in a vertical plane during unitary movement of said movable jaw and said shoe, and said flexible blade becoming tilted when the shoe moves relatively to the movable jaw and away from the clamping face of the movable jaw and tending to elongate and thus exerting a downward pull on the movable jaw, whereby said movable jaw is firmly pressed against said fixed guiding member, and at least a second flexible blade in parallel relation to said first mentioned flexible blade and connecting a rear and lower part of the shoe to a rear and upper part of the movable jaw.

7. A machine-tool vise according to claim 1, in which said movable jaw has the form of an inverted box comprising a front wall and a rear wall, an inverted U-shaped frame constituting three other walls of said box and connected respectively to an upper and to the lateral sides of said front and rear walls, and a bar connecting middle portions

of lower sides of said front and rear walls and extending under said shoe.

8. A machine-tool vise according to claim 1 further comprising at least one flexible blade connecting a forward and lower part of the shoe to a forward and upper part of the movable jaw, said flexible blade being continuously positioned in a vertical plane during unitary movement of said movable jaw and said shoe, and said flexible blade becoming tilted when the shoe moves relatively to the movable jaw and away from the clamping face of the movable jaw and tending to elongate and thus exerting a downward pull on the movable jaw, whereby said movable jaw is firmly pressed against said fixed guiding member.

9. A machine-tool vise according to claim 8, in which said movable jaw is provided under its clamping face with a portion spaced from the guiding member and elastically deformable by the

downward pull of said blade so as to lower the clamping face of the movable jaw.
